(57) **CLAIM**

The ornamental design for an RFID tire plug, as shown and described.

DESCRIPTION

FIG. 1 is a bottom perspective view of the new design for an RFID tire plug;

FIG. 2 is a top perspective view thereof;

FIG. 3 is a bottom view thereof;

FIG. 4 is a top view thereof; and,

FIG. 5 is a front view thereof, with the back view being a mirror image of the front view and with the left and right views being identical to the front view.

The broken lines shown illustrate portions of the RFID tire plug that form no part of the claimed design.

1 Claim, 3 Drawing Sheets(56)
